Bernard Crestin-Billet, Morez du Jura, France

Filed July 16, 1968, Ser. No. 12,793

Claims priority, application France Feb. 15, 1968

Term of patent 14 years

Int. Cl. D16—08

U.S. Cl. D57—1

Fig. 1.

Fig. 2.

Fig. 3.

Fig. 4.

FIG. 1 is a front perspective view of a pair of spectacles embodying my new design;

FIG. 2 is a rear view thereof, the elastic ribbon being fragmentarily shown for ease of disclosure.

FIG. 3 is a top plan view thereof;

FIG. 4 is again a top plan view of the spectacles folded.

I claim:

The ornamental design for a pair of spectacles, as shown and described.
